CLAIM

The ornamental design for a foldable water bottle, as shown and described.

DESCRIPTION

FIG. 1 is a front, top perspective view of a foldable water bottle, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1; and,

FIG. 10 is another perspective view of my new design for a foldable water bottle, shown in a configuration of use.

The dashed lines in the figures illustrate portions of the foldable water bottle that form no part of the claimed design. The dash dot dash lines in FIGS. 1 and 9 are for the purpose of illustrating the enlarged view indicators and form no part of the claimed design.
